(57) **CLAIM**

The ornamental design for a tool for placement in a wallet or other pocket-sized carrier, as shown and described.

DESCRIPTION

FIG. 1 is a front perspective view of a tool for placement in a wallet or other pocket-sized carrier, showing our new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is bottom view thereof.

In the drawings, broken lines illustrate portions of the tool that form no part of the claimed design.

1 Claim, 7 Drawing Sheets
